BANDALORE TOY OR SIMILAR ARTICLE

Thomas H. Ives, River Forest, Ill., assignor to Donald F. Duncan, Inc.

Application August 5, 1954, Serial No. 31,747

Term of patent 14 years

(Cl. D34—15)

To all whom it may concern:

Be it known that I, Thomas H. Ives, a citizen of the United States, residing at River Forest, Illinois, have invented a new and ornamental Design for a Bandalore Toy or Similar Article, of which the following is a specification, reference being had to the accompanying drawings, forming a part thereof, in which:

Fig. 2 is an end elevational view thereof.

Fig. 3 is a cross-sectional view thereof taken on line 3—3 of Fig. 2.

Fig. 4 is a cross-sectional view thereof taken on line 4—4 of Fig. 3.

I claim:

The ornamental design for a bandalore toy or similar article, as shown.
